UNITED STATES PATENT OFFICE

154,842

DESIGN FOR AN UPHOLSTERED SOFA

Einer Eck, Peru, Ind.

Application October 23, 1947, Serial No. 142,096

Term of patent 3½ years

(Cl. D15—11)

To all whom it may concern:

Be it known that I, Einer Eck, a citizen of the United States, residing at Peru, Miami County, Indiana, have invented a new, original, and ornamental Design for an Upholstered Sofa, of which the following is a specification, reference being had to the accompanying drawing, forming part thereof.

The ornamental beading and the veneer which it borders are continued around the top of the back of the sofa.

I claim:

The ornamental design for an upholstered sofa, as shown and described.

EINER ECK.
